UNITED STATES PATENT OFFICE.

WILLIAM J. COX AND SERVETUS C. GRAY, OF NASHVILLE, TENNESSEE.

LUBRICATOR.

SPECIFICATION forming part of Letters Patent No. 657,482, dated September 4, 1900.

Application filed May 26, 1900. Serial No. 18,170. (No model.)

To all whom it may concern:

Be it known that we, WILLIAM J. COX and SERVETUS C. GRAY, citizens of the United States, residing at Nashville, in the county of Davidson and State of Tennessee, have invented certain new and useful Improvements in Lubricators; and we do declare the following to be a full, clear, and exact description of the invention, such as will enable others skilled in the art to which it appertains to make and use the same.

The invention relates to lubricators, and more particularly to that class of lubricators designed for greasing traction-rails at curves to permit a street-car to more easily round the curve.

The object of the invention is to provide a device of this character which shall be under the complete control of the motorman or gripman, who upon approaching the curve may move the discharge end of the lubricator into contact with the inner side of the wheel-flange, which will distribute the lubricant upon the guard-rail at the curve.

With this object in view the invention consists in certain features of construction and combination of parts, which will be herein-after fully set forth.

In the accompanying drawings, Figure 1 is a side view of the front portion of a street-car, illustrating the application of our invention, and Fig. 2 is a bottom plan view. Fig. 3 is a longitudinal sectional view through the grease-box. Fig. 4 is a bottom plan view of the box.

Referring to said drawings, 1 denotes the platform of a street-car, and 2 the front wheels thereof.

3 denotes the grease-box, provided with a removable cover 4 and a tapering outer end 5. One side of the grease-box and tapering-end are flat and provided with guide-strips 6. In the flat side of the tapering end of the grease-box is formed a discharge-orifice 7.

8 denotes a discharge-tube, one side of which is flat and is provided with an aperture 9 and with a bar 10, which is adapted to slide between the guide-strips and is connected at its inner end to the inner end of the grease-box by a coil-spring 11, which exerts its energy to draw the discharge-tube inwardly, so that its orifice will be unaligned

with the orifice in the outer end of the grease-box. The extreme outer end of the discharge-tube is secured to a brush-head 12, which is provided with a central discharge-aperture 13.

14 denotes a removable spring-actuated plunger located in the grease-box and connected to the removable cover and serves to force the lubricant, which is in a semifluid condition or in the form of paste, through the discharge-opening 7 in the outer end of said box.

15 denotes a cam journaled to the flat side of the grease-box and provided with an enlargement 16, which is adapted to be moved into engagement with the inner end of the discharge-tube and force the same outwardly, so as to align its opening with the opening in the outer end of the grease-box. A spring 17 is connected to the cam and serves to restore it to its normal position. To check the rotation of the cam and to prevent its enlargement being moved beyond the inner end of the discharge-tube in the act of depressing it, I provide the periphery of the cam with a stud 18, which is adapted to engage a fixed stop 19, secured to the side of the box.

Any suitable means may be provided for rotating the cam; but those shown in the drawings are preferred and consist of a crank-wheel 20, the crank 21 of which is connected to a crank 22 of the cam by a link 23. A push-rod 24 is pivoted to the crank-wheel and extends up through the platform of the car and is within convenient reach of the motorman's foot.

In operation in approaching a curve if it be desired to lubricate the guard-rails thereof the push-rod is depressed by the motorman. This through the intermediate mechanism aligns the aperture of the discharge-tube with the aperture in the outer end of the grease-box, and the grease within said box being under pressure of the spring-actuated plunger is forced through the aligned apertures and out through and between the fibers of the brush-head. In the act of aligning the two apertures the discharge-tube is forced outward, with the brush-head in engagement with the inner side of the wheel-flange, so that the grease is discharged directly upon the flange of the wheel and will be distributed upon the

rail, thus avoiding the necessity of employing additional labor, as is now the custom, to go from end to end of the road and grease the tracks.

5. From the foregoing description, taken in connection with the accompanying drawings, the construction, operation, and advantages of our invention will be readily understood without requiring an extended explanation.

10. The device is exceedingly useful for the purpose for which it is designed and may be placed upon the market at a comparatively small cost.

15. Various changes in the form, proportion, and the minor details of construction may be resorted to without departing from the principle or sacrificing any of the advantages of this invention.

Having thus fully described our invention, 20. what we claim as new, and desire to secure by Letters Patent of the United States, is—

25. 1. In a lubricator of the character described, the combination with the grease-box provided with a discharge-opening, of a movable discharge-tube connected to the grease-box and provided with an opening, and means for alining the two openings to permit of the discharge of the lubricant from the grease-box into and through the discharge-tube, substantially as set forth.

30. 2. In a lubricator of the character described, the combination with the grease-box provided with a discharge-opening, of a discharge-tube provided with an opening, and means for simultaneously alining the two openings and moving the outer end of the discharge-tube into engagement with a moving body, substantially as set forth.

35. 3. In a lubricator of the character described,

the combination with the grease-box provided 40 with a discharge-opening, of a discharge-tube connected to said grease-box and provided with an opening, means for normally holding the openings in unaligned relation, and means for moving the discharge-tube to aline said 45 openings and permit of the discharge of the lubricant through said openings, substantially as set forth.

4. In a lubricator of the character described, the combination with the grease-box provided 50 with a discharge-opening, of a discharge-tube connected to said grease-box and provided with an opening, means for normally holding the openings in unaligned relation, means for moving the discharge-tube to aline said 55 openings and permit of the discharge of the lubricant through said openings, and a spring-actuated plunger within the grease-box for forcing the lubricant through said openings, substantially as set forth.

5. In a lubricator of the character described, the combination with the grease-box having an opening, of a movable discharge-tube provided with a normally-unaligned opening, a cam provided with an enlargement arranged 60 to contact with and move the discharge-tube to aline said openings, means for actuating the cam, and means for restoring the cam to its normal position, substantially as set forth.

In testimony whereof we have hereunto set 70 our hands in presence of two subscribing witnesses.

WILLIAM J. COX.
S. C. GRAY.
